UNITED STATES PATENT OFFICE.

CHARLES A. MAY, OF TRENTON, NEW JERSEY, ASSIGNOR TO THE MADDOCK POTTERY COMPANY, OF SAME PLACE.

DESIGN FOR A BOWL.

SPECIFICATION forming part of Design No. 25,791, dated July 21, 1896.

Application filed June 6, 1896. Serial No. 594,631. Term of patent 7 years.

To all whom it may concern:

Be it known that I, CHARLES A. MAY, a citizen of the United States, residing at Trenton, in the county of Mercer and State of New Jersey, have invented and produced a new and original Design for Washbowls, of which the following is a specification.

In the accompanying drawings, Figure 1 represents a top plan view of the bowl, and Fig. 2 a side elevation.

The leading feature of the design consists in the lateral extensions *aa* on opposite sides of the upper part of the bowl, in which extensions are elongated openings *bb*.

The upper part of the bowl is flared outward, and on its upper surface are embossed figures and the edges are scalloped.

What I claim is—

The design for a bowl substantially as herein set forth.

In testimony whereof I affix my signature in presence of two witnesses.

CHAS. A. MAY.

Witnesses:

J. W. HENNEY,
A. H. LEDDEN.
